UNITED STATES PATENT OFFICE.

JAMES CALVIN ROGERS, OF BIRMINGHAM, ALABAMA.

GARTER.

1,228,139.

Specification of Letters Patent. Patented May 29, 1917.

Application filed January 25, 1916. Serial No. 74,246.

To all whom it may concern:

Be it known that I, JAMES C. ROGERS, a citizen of the United States, and a resident of Birmingham, in the county of Jefferson 5 and State of Alabama, have invented a new and Improved Garter, of which the following is a full, clear, and exact description.

The object of the invention is to provide a new and improved garter which is simple 10 and durable in construction, arranged to permit the user to conveniently place the garter in position on the leg and attach it to the hose or stocking, and to draw the leg band taut around the calf of the wearer's 15 leg by the downward pull exerted by the hose or stocking.

In order to accomplish the desired result, use is made of a leg band provided at its 20 ends with guiding means and a cord attached at one end to one end of the leg band and extending around the guiding means at the other end of the leg band, then returning and engaging the guiding means on the end of the leg band to which the cord 25 is attached and to then extend downwardly to support a gripping device for engagement with the hose or stocking.

A practical embodiment of the invention is represented in the accompanying drawings 30 forming a part of this specification, in which similar characters of reference indicate corresponding parts in all the views.

Figure 1 is a side elevation of the garter as applied;

Fig. 2 is an enlarged sectional plan view 35 of the same on the line 2—2 of Fig. 1;

Fig. 3 is an enlarged cross section of the same on the line 3—3 of Fig. 1;

Fig. 4 is a side elevation of a modified 40 form of the garter; and

Fig. 5 is an enlarged sectional plan view of the same on the line 5—5 of Fig. 4.

The leg band 10 is preferably of a non- 45 elastic material and is provided at one end with an adjusting buckle 11 for lengthening and shortening the leg band 10 to suit the size of the calf of the leg of the wearer.

The loop 12 at this end of the leg band 10 50 engages a slot 13 formed in a metallic plate 14 provided with a return bend 15 to form a housing for a pulley 16 around which passes a cord 17 attached at one end by suitable fastening devices 18 to the other end of the leg band 10 and which other end is 55 provided with an angular terminal 19 extending downwardly, as plainly shown in

Fig. 1. The cord 17 after leaving the pulley 16 passes around another pulley 20 journaled on a plate 21 attached by a tape 22 to the angular terminal 19, as plainly 60 shown in Fig. 1. The plate 21 is provided with a return bend 23 similar to the return bend 15 to overlie the pulley 20 and to allow of readily passing the cord 17 over the return bend into engagement with the pulley 65 20. The free end of the cord 17 extends downwardly and is provided with a suitable gripping device 24 adapted to engage the hose or stocking 25 to be supported by the garter. It will be noticed that when the 70 garter is in use the stocking 25 exerts a downward pull by the gripping device 24 on the cord 17 and as the latter passes around the pulleys 20 and 16, it is evident that a pull is exerted on the ends of the leg 75 band 10 to draw the latter tight around the calf of the wearer's leg. It is understood that in using the garter the cord 17 is passed over the pulleys 16 and 20 to close 80 the garter around the wearer's leg, and the gripping device 24 is engaged with the hose or stocking. When it is desired to disconnect the leg band 10 from the wearer's leg the cord 17 is slipped out of engagement 85 with the pulley 16 to open the garter. From the foregoing it will be seen that any tendency of the hose or stocking 25 to slide down on the wearer's leg causes a pull on the cord 17 to draw the leg band 10 tight on the wearer's leg and consequently the garter is 90 not liable to slip down on the leg whenever there is a downward tendency of the hose or stocking. By the arrangement described, the garter readily adjusts itself to the action 95 of the muscles of the leg especially while the leg is in motion. The leg band 10 may be made of silk, cotton, leather or other suitable material, but is preferably made of some material which can be rendered non-absorbent. The plate 14 is preferably 100 covered at the back with a suitable fabric material 26 to prevent the metallic plate from coming in direct contact with the skin on the wearer's leg.

In the modified form shown in Figs. 4 105 and 5, the leg band 30 is provided at one end with an adjusting buckle 31 to form a loop 32 engaged by a hook 33 adapted to be hooked on a stud or pin 34 formed on a plate 35 secured on the face of a fabric 110 material 36 by the use of stitches 37 extending through slots 38 formed in the plate 35.

On the face of the plate 35 is secured a 5 semicircular tube 40 having flaring ends 41 and through which extends a cord 42 fastened at one end by suitable fastening devices 43 to the leg band 30 at the angular end 31 thereof. The cord 42 also passes through a segmental tube 44 formed or secured on a plate 45 attached by stitches 46 to the angular terminal 31 of the leg band 10 30. The free end of the cord 42 is provided with a gripping device 50 of any approved construction adapted to engage the hose or stocking 51 to be supported. It will be noticed that by this arrangement any downward 15 tendency of the hose or stocking 51 exerts a pull on the cord 42 to draw the leg band 30 tight around the calf of the wearer's leg. When it is desired to open the garter the hook 33 is disengaged from the pin or 20 stud 34, and when it is desired to close the garter the hook 33 is engaged with the stud 34. By providing the segmental tubes 40 and 44 with flaring ends the cord 42 is not liable to chafe while sliding in the said 25 tubes.

It is understood that the pulleys 16 and 20 and the tubes 40 and 44 form guiding means for the cords 17 and 42 to slide in freely without undue friction and chafing. By 30 locating the pulley 20 and the tube 44 on the angular terminals 19 and 31 of the leg bands 10 and 30, the two horizontal runs of the cords 17 and 42 are kept spaced apart and parallel to insure a straight horizontal 35 pull on the ends of the leg bands 10 and 30.

Having thus described my invention, I claim as new and desire to secure by Letters Patent:

1. A garter comprising a leg band, a flexible element permanently and fixedly secured at one end to one end of the leg band, and a hose engaging means at the other end and tubular guides at the ends of said leg band, said guiding means slidably engaged 45 by said flexible element.

Copies of this patent may be obtained for five cents each, by addressing the "Commissioner of Patents, Washington, D. C."

2. A garter comprising a leg band, a cord permanently and fixedly secured at one end to one end of the leg band and provided at its other end with a hose gripping device, plates attached to the ends of said leg band, 50 and tubular guides mounted on said plates, said tubular guides slidably engaged by the said cord.

3. A garter comprising an open leg-band consisting of a central and two end portions, 55 one end portion having a downwardly bent terminal, a cord having one end permanently and fixedly secured to the portion carrying the bent terminal and provided at its other end with a gripping device adapted 60 to engage the hose to be supported, and guiding means carried by both end portions, one of said guiding means mounted on the downwardly bent terminal.

4. A garter, comprising a leg band provided at one end with a hook, a cord attached to the other end of the said leg band, a plate having a stud adapted to be engaged by the said hook, a plate attached to the end of the leg band adjacent the said fixed end of the 70 cord, guiding means on the said plates and slidably engaged by the said cord, and a gripping device on the free end of the cord.

5. A garter, comprising a leg band provided at one end with a hook, a cord attached to the other end of the said leg band, a plate having a stud adapted to be engaged by the said hook, a plate attached to the end of the leg band adjacent the said fixed end of the cord, segmental tubes fixed on the 80 said plates and through which extends the said cord, and a gripping device on the free end of the said cord.

In testimony whereof I have signed my name to this specification in the presence of 85 two subscribing witnesses.

JAMES CALVIN ROGERS.
